MACHINE FOR MAKING MATCH FUSES AND
THE LIKE

Joseph Gioiosa, East Milton, Mass.

Application November 10, 1938, Serial No. 239,841

8 Claims. (Cl. 57—35)

This invention relates to improvements in machines for making impregnated twisted cords, and one of the objects of the invention is to provide a machine having a reservoir containing 5 a suitable impregnating material with means for continuously drawing a plurality of fibrous strands in converging relation through the material in the reservoir thoroughly to impregnate the several strands and simultaneously to twist 10 the strands within the material thereby to embed the impregnating material within the entwined strands.

Another object of the invention is to provide means for coating the impregnated and entwined 15 strands to insure a uniform product.

More particularly the invention relates to machines for making pyrotechnic fuses, such as are known as a quick match fuse or a black match fuse which comprises a plurality of strands of 20 fibrous material impregnated with a suitable combustible match-impregnating composition such as gun powder. Fuses such as are known as quick match fuse or black match fuse have heretofore been made by hand or by the use of 25 crude slowly operated machines, such as machines in which a plurality of strands are drawn by a hand operated reel through the match-impregnating composition and associated in parallelism without twisting.

30 One of the principal objects of the present invention is to provide a machine for making a quick match or black match of very considerable length in which a plurality of fibrous strands are drawn in converging relation through the combustible match-impregnating composition and simultaneously twisted within said material to embed the material within the entwined 35 strands, and which can be operated at a very greatly increased speed over usual machines and methods of making such articles.

40 A further object of the invention is to provide a machine for making quick matches or black matches and in which the impregnated or entwined strands are coated with a similar composition to insure uniformity in the burning of the fuses when severed to predetermined lengths.

45 A further object of the invention is to provide a machine of the character described with novel mechanism for traversing the impregnated and entwined strands upon a reel in such manner that adjacent spirals are non-contacting with means for stopping the machine when the reel 50 is filled or a predetermined length is wound upon the reel.

55 A further object of the invention is to provide

a machine of the character described in which the restarting of the machine will cause the traversing mechanism to move in the reverse direction, with similar means for stopping the machine at the end of said traverse. 5

A further object of the invention is to provide automatic means operable by the traversing mechanism for stopping the machine with manually actuated means operable upon restarting the machine to reverse the direction of movement 10 of the traversing mechanism. 10

Another feature of the invention is to provide traversing means with a reservoir for the coating material and having means by which the reservoir can be readily removed from the traversing 15 mechanism.

Another object of the invention is to provide mechanism for actuating the reel, the traversing mechanism, the mechanism for drawing the strands through the reservoir, and the means for 20 twisting the strands in suitably timed relation to produce a uniformly impregnated and coated cord or match. 20

Another feature of the invention consists in providing means for protecting the traversing 25 mechanism from drippings of the impregnating or coating composition.

Another feature of the invention consists in providing mixing mechanism for the impregnating composition which will insure uniformity 30 thereof with means for delivering the same to the coating reservoir.

These and other objects and features of the invention will more fully appear from the following description and the accompanying drawings and will be particularly pointed out in the 35 claims.

A preferred embodiment of the invention is shown in the drawings, in which,

Fig. 1 is an end elevation of a machine for 40 making impregnated twisted cord;

Fig. 2 is a side elevation, the central portion being broken away to indicate that the reel and its actuating mechanism may be of any suitable length;

Fig. 3 is a plan view similarly broken away;

Fig. 4 is a detail plan view showing the screw of the traversing mechanism for guiding the impregnated twisted cord to the reel (not shown) and the automatic stop mechanism and the 50 mechanism for reversing the direction of rotation of the screw;

Fig. 5 is a side elevation of the mechanism shown in Fig. 4; and,

Fig. 6 is a detail sectional view of the reversing 55

gear mechanism on line 6—6 Fig. 4, viewed from the right toward the left, illustrating the reversing mechanism, and means for actuating the same.

5 The machine shown in the drawings comprises a base or platform 1 which is supported upon suitable legs 2 and has mounted upon it an upwardly extending post 3 provided near its upper end with an adjustable collar upon which 10 is clamped parallel laterally extending ends 4 of a conical ring 5 supporting a conical reservoir 6 for the impregnating material. The upper end of the reservoir 6 desirably is provided with a more flaring upward extension 7. The lower end 15 of the conical reservoir is provided with a lining or bushing 8, preferably of rubber or other yieldable material, having a vertical aperture therethrough through which the twisted strands of fibrous material are led and which are guided 20 therefrom to a suitable reel. The platform has also mounted upon it a vertical standard 9 having a laterally extending arm 10 which overhangs the vertical axis of the reservoir 6. A vertical shaft 11, which is rotatably mounted in a suitable 25 journal in the end of the overhanging arm 10, has secured to it a pulley 12 which desirably rests upon a boss at the end of the arm 10. The lower end of the shaft 11 has secured to it a collar 13 which supports a carrier 14 upon which 30 are mounted a plurality of spindles 15 each of which carries a cop or tube 16 of cotton thread, string, or other suitable fibrous material. The carrier 15 is fixedly secured to the shaft 11 and is spaced from the under side of the arm 10 by 35 a suitable spacing sleeve.

Suitable means hereinafter to be described are provided for rotating the carrier 14 thereby to twist the strands of fibrous material. The strands 17 of fibrous material are led downwardly 40 through the impregnating material 18 in converging relation and are drawn axially downwardly through the vertical aperture in the bushing 8 around a guide pulley 19.

The axle of the guide pulley 19 is mounted 45 upon suitable standards and desirably is surrounded by a cylindrical wall 20 which forms a receptacle to receive any of the impregnating material which may leak through the aperture in the bushing 8. However, the bushing is such 50 as effectively to prevent the escape of any substantial amount of the impregnating material.

As the strands are thus led convergingly downwardly through a very considerable depth of impregnating material each strand is thoroughly 55 impregnated with said material. By reason of the rotation of the carrier 14 upon which the tubes or cops of fibrous material are mounted, impregnation of the strands 17 is facilitated and the strands are twisted during their progress 60 through the impregnating material into the form of a cord and the impregnating material is also embedded within the entwined strands, thereby forming a cord in which the fibrous material of the strands are thoroughly impregnated 65 with said material and additional material bound within the entwined strands of the cord.

The bushing 8 in the lower end of the reservoir acts as a die to produce uniform twisting of the 70 strands and to insure uniform cross sectional area of the cord which is thus entwined and filled with impregnating material.

The impregnated cord or match 21 is led upwardly from the pulley 19 over a vertical pulley 75 22, thence downwardly beneath a vertical pulley

23, and thence around a horizontal pulley 24 to a traveling pulley 25 which is mounted upon a traversing mechanism carrying a guide for directing the same to a positively driven reel upon which the cord or match is wound in non-contacting spirals. The reel may be made of sufficient size and capacity to hold a great length of cord or match and is detachably mounted in a suitable frame in such manner that the reel can be readily removed and transported to a 10 suitable drying chamber or again mounted on suitable apparatus to permit drying of the impregnating material.

A convenient form of reel which is illustrated 15 herein comprises a framework having a central shaft 26 and a series of sets of radial arms 27, preferably four in number, and extending at right angles to each other and connected together at their ends by bars 28 which extend in 20 parallelism to the axis of the reel.

In order detachably to support the reel shaft in such manner that it may be readily removed and transported to the drying mechanism, one end of the reel shaft 26 is provided with an angular socket 29 adapted to fit upon a complementary extension of a reel driving shaft 30 which is mounted in suitable vertical standards 31 and 32. The opposite end of the reel shaft 26 is likewise provided with a socket 33 adapted to receive the end of a stub axle 34 which is rotatably mounted in a suitable bearing in a vertical standard 35. The stub axle has secured to it a collar 36 and a spring 37 interposed between the collar 36 and the standard 35 serves to maintain the end of the stub axle normally in engagement with the socket in the reel shaft 26. The opposite end of the stub axle is provided with a handle member 38 by means of which the stub axle can be drawn lengthwise against the force of the spring 37 to detach it from the reel shaft 40 30 40 26 and also to permit the reel shaft to be disengaged from its driving shaft so that the reel can be readily removed and replaced.

Suitable traversing means are provided for 45 guiding the impregnated cord or match 21 in non-contacting spirals along the reel until the reel is filled or a predetermined length of cord or match wound upon it.

In the preferred construction illustrated here- 50 in the guiding mechanism for the cord is carried upon a suitable carriage 39 which is mounted upon parallel track members 40 which extend in parallelism with the reel and is caused to traverse the length of the reel, or other such distance as may be desired, by a screw and a cooper- 55 ating nut upon the carriage, reversing mechanism being provided to enable the screw to propel the carriage in opposite directions.

Means are also provided for automatically 60 stopping the machine when the carriage has traveled a predetermined distance such as approximately to the end of the reel in either direction and manually operable mechanism is provided for starting the machine and simultaneously reversing the direction of travel of the 65 carriage. By reason of this mechanism the reel can be removed from the machine after the guide-supporting carriage has traveled in one direction, a new reel substituted, and the carriage caused to travel in the opposite direction to fill 70 the substituted empty reel without the necessity of returning the carriage to its original starting point, thereby enabling a considerable saving of time which otherwise would be required in filling successive reels.

As illustrated herein the carriage 39 has secured to it at one end a downwardly extending bracket 41, see Fig. 1, upon which are mounted upper and lower wheels 42 and 43 which engage respectively the upper and lower surfaces of the horizontal flange of the angle iron track member 40. A bracket 44, which is secured to the opposite end of the carriage 39, has mounted upon it a wheel 45 which engages the upper face 10 of the horizontal flange of the other track member 40.

In the preferred construction illustrated the guide member for the impregnated cord 21 also comprises a supplementary reservoir containing 15 a coating composition which desirably is of substantially the same character as the composition for impregnating strands of the cord or match. The purpose of this coating mechanism is to apply additional composition to the impregnated cord or match and where a match is produced to insure uniformity in the burning of the match or the match sections into which the match may be divided for use as fuses.

In the construction illustrated herein the coating and guiding mechanism for the cord or match is in the form of a reservoir 46 which may be of rectangular form and which is mounted upon a base 47 which rests upon and is detachably secured to the carriage 39. The reservoir 46, which 30 is supplied with coating composition of suitable character preferably a somewhat thinner composition than the impregnating composition, is provided with a guide and seal 48 through which the cord or match 21 is led and at its opposite 35 end with a somewhat longer guide and seal 49 from which the cord or match 21 is led to the reel. The base 47 of the reservoir and guide has pivotally secured to one of its ends a depending bracket 50 upon the lower end of which is mounted a guide wheel 51 which engages the under face of the track member 40 beneath the carriage-supporting wheel 45.

By reason of this construction the carriage is supported upon the track by the wheels 42 and 46 and any tilting of the carriage or the base of the guiding member is prevented by the guide wheels 43 and 51 which underlie the track members 40. This construction also enables the reservoir to be conveniently removed for the purpose of substituting a different guide member or reservoir.

It will be understood that while in the preferred construction coating means is employed, other types of guides for reeling the cord may be employed.

The preferred mechanism for traversing the carriage illustrated herein comprises a nut 52 which is secured to the under face of the carriage 39 and engages a screw 53 which extends longitudinally of the reel and in parallelism therewith.

Suitable driving mechanism is provided for rotating the reel, for actuating the guide-supporting carriage to traverse the impregnated cord or match upon the reel, for driving the pulley 63 which draws the cord or match through the reservoir for rotating the carrier upon which the thread tubes or cops are supported to twist the strands of fibrous material, and for actuating a suitable mixer from which the impregnating material is delivered to the main reservoir 6 in properly timed relation to accomplish the purpose of the invention. The main driving shaft 54, which is rotated from any suitable source of power (not shown) is journaled in a suitable bracket 55 in the base of the standard 32, and is

provided adjacent its end with a worm 56 which engages a worm wheel 57 upon a shaft 58 which is journaled in suitable bearings on said standard. A spur gear 59, which is fixedly secured to the shaft 58, engages a complementary spur gear 60 upon a countershaft 61 which is mounted in said standard and which has mounted upon its opposite end a sprocket wheel 62 which drives a sprocket chain 63 which in turn drives a sprocket 64 which is fixedly secured to the reel driving shaft 30 the angular end of which detachably engages one end of the reel shaft 26 and rotates the reel. The reel driving shaft 30 has secured to it a large pulley 65 which drives a belt 66, the leads of which pass over suitable guide pulleys 15 67 and 68 and engage and drive the pulley 12 upon the end of the shaft 11 which supports the carrier for the thread tubes or cops of the fibrous strands which when impregnated and twisted 20 form the cord.

The shaft 58, which is driven by the worm 56 and worm wheel 57, has secured to its opposite end a sprocket 69 which drives a horizontal sprocket chain 70 which in turn drives a sprocket wheel 71 upon a shaft 72 which is mounted in 25 journals in the lower frame of the machine and which has on its end a sprocket wheel 73, Fig. 2. The sprocket wheel 73 drives a vertical sprocket chain 74 which in turn drives a sprocket pinion 75 upon a shaft 76 the ends of which are mounted 30 in a suitable stand 77 and in bearing members mounted upon the base of the standard 9. The shaft 76 has secured to its opposite end a bevel gear 78 which meshes with a companion bevel gear 79 upon a shaft 80 upon the opposite end of 35 which is mounted the drawing pulley 22 for the impregnated cord or match. The pulley 22 acts in conjunction with the reel continuously to draw the fibrous strands through the reservoir while they are being twisted into the cord and as 40 above described the cord is guided from the pulley 22 to the guide of the traversing mechanism by the pulleys 23, 24 and 25.

The shaft 72, which is mounted in suitable bearings upon the base or platform of the machine, has fixedly secured to it a gear 81 for 45 driving the screw 53 through suitable reversing mechanism adapted to cause the guide, or reservoir and guide, for the cord to wind the cord in spirals upon the reel.

A preferred form of reversing mechanism is illustrated together with automatic controlling mechanism in detail in Figs. 4, 5, and 6. The mechanism for transmitting rotation from the gear 81 which is positively driven in one direction 55 to the gear 82 upon the screw 53 in such manner as selectively to rotate the screw in reverse directions comprises a hook-shaped lever 83 the shorter arm of which is pivotally mounted upon a reduced cylindrical end portion 84 of the screw, 60 which is mounted in suitable bearings carried by the base, the gear 82 being secured to this reduced portion of the screw shaft. The hook-shaped lever 83 has rotatably mounted in it lower and upper meshing spur gears 85 and 86 so arranged that when the longer arm of the lever 83 is in vertical position, as illustrated in Fig. 6, neither of the gears 85 and 86 will mesh with the driving gear 81 upon the shaft 72. When, however, the longer arm of the lever 83 is swung to 70 the right from the position illustrated in Fig. 6, the gear 86 will mesh with the gear 81 and will thereby transmit rotation to the gear 82 in one direction. When, however, the longer arm of the lever 83 is swung to the left the gear 85 will 75

be thrown into mesh with the gear 81 thereby transmitting rotation from the gear 81 through the gears 85 and 86 to the gear 82 and rotating it in the reverse direction. By reason of this construction therefore the nut 52 and the carriage 39 for the guide or reservoir will be caused to move alternately in opposite directions lengthwise of the reel.

Suitable means are employed to stop the machine when the carriage with its guide has approached the end of the reel with manually operable means for reversing the direction of movement of the carriage when the machine is restarted. This mechanism as illustrated herein comprises a reversing bar 87 which is slidably mounted in suitable bearing members extending upwardly from the floor or base of the machine and is provided with adjustable abutment blocks 88 and 89 positioned to be engaged by the nut 52 which is mounted on the screw and is secured to the under face of the carriage 39. As the nut approaches the end of traverse in one direction it engages the abutment 88, as illustrated in Fig. 3, and upon continued movement of the nut 25 moves the reversing bar 87 lengthwise. Similarly when the nut has traversed the screw in the opposite direction it engages the abutment block 89 on the reversing bar 87 and moves the reversing bar in the opposite direction. The movement of 30 either of these abutment blocks by the nut is such as to position the reversing mechanism in neutral position, shown in Fig. 6, and also to actuate mechanism for stopping the machine. The manually operated mechanism for restarting the machine is so arranged as to continue the movement of the reversing bar in the same direction as it was moved by the nut and so to shift the reversing gears 86 and 85 as to rotate the screw in the reverse direction.

40 The mechanism for accomplishing this purpose comprises a plate 90 which is fixedly secured to and extends horizontally from the end of the reversing bar 87 and has an upwardly offset portion 91 which is slidably mounted in guideways 45 92 upon a suitable stand 93. The offset portion 91 of the plate 90 is provided with a cam slot the opposite ends 94 and 95 of which are inclined or curved in opposite directions from a central neutral position in the cam slot. The cam follower 96 is in the form of a vertical pin the lower end of which engages the cam and the reduced upper end 97 of which is mounted in a slot 98 in a U-shaped cap piece 99 which is secured to the stand 93. The central portion of the follower pin is reduced and is provided with a horizontal trunnion 100 upon which is mounted a twisted link 101 the opposite end of which is pivotally secured by a bolt 102 to the longer arm 83 of the hook-shaped lever which carries the gears 85 and 86. Obviously when the plate 91 is moved lengthwise in one direction the follower will be carried from a neutral position laterally so as to move the gear 86 of the reversing mechanism into engagement with the driving gear 81 and thereby rotate the screw in one direction. Conversely when the plate 91 is moved in the opposite direction the follower will be moved by the oppositely inclined portion of the slot in the opposite direction and will thus actuate the lever 83 to remove the gear 86 from engagement with the gear 81 and cause the gear 85 to mesh with the gear 81 so that power will be transmitted from the gear 81 through the gears 85 and 86 to the gear 82 on the screw and rotated in the opposite direction.

In view of the fact that it is necessary to remove a filled reel and substitute an empty one before the reversing operation takes place means actuated by the reversing bar are provided for stopping the machine when the cam follower 96 is in neutral position. This is accomplished in the mechanism illustrated by securing to the plate 90, which constitutes an extension of the reversing bar 87, a supplemental cam plate 103 which desirably may be separated from the plate 90 by a spacer 104 so that the plate 103 is in substantially the same plane as the offset portion 91 of the plate 90. The cam plate 103 is provided with a cam slot having a central neutral portion and end portions 105 and 106 which extend in angular relation thereto, as illustrated in Fig. 4. A cam follower 107 extends downwardly into the cam slot from a block 108 which is slidably mounted upon the plate 103 and has secured to it a rod 109 the opposite offset end of which is pivotally connected by a bolt 110 to the lower arm 111 of a lever (Figs. 1 and 4), and a rod 112 which is pivotally connected to the lower end of the arm extends to and is suitably connected to a belt shipper, clutch or motor control for stopping the machine. When the cam follower 107 is moved by the cam in the plate 103 to the neutral position designated as "N" in Fig. 4, the lever 111, which is illustrated in Fig. 1 as in running position will be moved to substantially vertical position, thereby forcing the rod 112 to the right, Fig. 1, and actuating the belt shipper or other mechanism for stopping the machine. The lever 111 may if desired be provided with an upwardly extending handle portion 111x which may be actuated as an emergency lever when the machine is running to move the rod 109 lengthwise and force the cam follower 107 from the inclined portion 105 or 106 in the cam slot in the plate 103 to neutral position and thereby stop the machine. Such actuation of the emergency lever 111x can be made only when the machine is running as it cannot be actuated to move the follower 107 from neutral position into the inclined portion 105 or 106 of the cam slot when the machine is stopped.

The reversing bar 87 is provided with a bifurcated forward end 113 which is pivotally connected to a starting lever 114 the lower end of which is fulcrumed upon a suitable bracket 115 secured to the floor or base of the machine.

It has heretofore been explained that when the abutment 88 is engaged by the nut and moved endwise to the neutral position illustrated in Fig. 4, the cam plate 103 will be so moved as to place the cam follower 107 in neutral position thereby stopping the machine, and that in order to start the machine the reversing bar is moved further in the same direction, as illustrated by the dotted position to the left of the position in which the abutment is engaged by the nut in Fig. 4. Actuation of the starting lever therefore will move the cam plate 103, shown in Fig. 4, so that the cam follower 107 will engage the inclined end 105 of the cam slot, thereby moving the rod 109 and the lower arm of the lever 110 to running position and simultaneously shifting the driving belt or the motor control to operating position.

When the carriage has traversed lengthwise of the reel in the opposite direction the nut 52 will engage the other abutment 89 on the reversing bar and move it longitudinally in the opposite direction until the cam follower 107 is in neutral position. To start the machine the 75

starting lever is moved in the opposite direction from that previously described, thereby causing the cam follower 107 to move along the inclined portion 106 of the cam slot, thus again actuating 5 the belt-shifting mechanism or motor controlling mechanism in the manner above described. When the reversing bar 87 is moved in either direction the reversing mechanism, which is controlled by the cam slot in the cam plate 91, will 10 simultaneously actuate the gear shifting mechanism to cause the screw to be rotated in the proper direction to propel the carriage lengthwise of the reel so that the cord will be wound spirally upon the reel as above described. 15 15. In order to provide for continuous operation of the machine and to maintain a proper consistency of the impregnating material means desirably are provided for continuously or intermittently replenishing the impregnating material 20 in the reservoir 6. In the construction illustrated in Fig. 1 a mixing tank 116 is mounted upon a suitable support 117 at a considerably higher level than the reservoir 6. This mixing tank is of sufficient capacity to contain a large 25 amount of the impregnating material which when a fuse or black match is to be made may be of gun powder or other suitable combustible material mixed or dissolved in water to a suitable fluidity. The mixing tank 116 is provided 30 with a suitable mixer or agitator, such as arms 118 extending radially from a vertical shaft 119 which is mounted in a suitable bearing 120 in the supporting frame. The arms 118 may be provided with suitable vanes 121 preferably pivotally mounted at the outer ends of said arms. 35 Any suitable means may be provided for driving the agitator. As illustrated herein the shaft 30, see Figs. 1 and 2, is provided with a pulley 122 which drives a belt 123 the leads of which pass over suitably supported guide pulleys 124 and 40 125, and engage and drive the pulley 126 which is fixedly secured to the vertical shaft 119 of the mixer. Communicating pipes or conduits 127 and 128 lead from the mixing tank to the reservoir 6. A suitable valve 129, which desirably is 45 provided at the junction of the pipes 127 and 128 is provided with an operating handle 130 which may be so manipulated as to provide a suitable passage for delivering the impregnating composition to the reservoir at a predetermined rate or which may be intermittently operated to replenish the supply of impregnating material in 50 the reservoir.

A further feature of the invention comprises 55 means for preventing the dripping of the impregnating material upon the screw and also minimize the settling of dust upon it. This mechanism as illustrated herein comprises a wide belt 131 of flexible material, such as canvas, rubber, 60 or leather, which is secured to the under face of the carriage 39 and extends horizontally above the screw around guide rollers 132 and 133. The opposite ends 134 and 135 of the belt 131 are connected to a cord or cable 136 which passes 65 over guide pulleys 137 and 138 which may be conveniently suspended from brackets mounted on the ceiling of a room.

By reason of this construction the belt will be pulled lengthwise by the carriage in such manner that it will always protect the screw 53 in the manner above described.

In the operation of the machine in continuously making impregnated and coated fuses (as well as other forms of impregnated and 75 coated cords), the impregnating material, such

as gun powder is placed in the mixing tank 116 and agitated therein with water or other suitable solvent or diluting agent. It is supplied from the mixing tank to the conical reservoir 6. The strands of fibrous material, which are 5 mounted on the rotating carrier 15, are led downwardly through the reservoir, and the bushing or die at its lower end. The rotation of the carrier 14, which is positively driven in the manner above described, moves the strands circularly 10 within the impregnating mixture, thereby agitating the mixture and securing complete impregnation of the strands. This rotation also twists the strands into the form of a cord and additional material is entwined within the 15 strands. As the twisted strands or cord are drawn through the bushing at the lower end of the reservoir, they are compacted into a cord of uniform cross section. The strands and resulting cord are drawn by the conjoint action 20 of the positively driven pulley 22 and the positively rotated reel. The strands pass downwardly from the driven pulley 22, around the guide pulleys 23 and 24, and thence around the pulley 25 which is mounted upon the traveling 25 carriage and directed by the pulley 25 through the guide 48 into the supplemental reservoir containing the coating material. The cord passes through the guide 49 to the reel.

The carriage is moved longitudinally of the 30 reel at a predetermined rate by the screw 53, thereby laying or guiding the impregnated cords or match in such manner as to wind it upon the reel in non-contacting spirals. When the carriage approaches the end of the reel its nut engages one of the abutments 88 or 89, as the case may be, thereby moving the reversing bar 87 lengthwise and causing the cam plate 103 to 35 actuate mechanism for stopping the machine and simultaneously causing the cam plate 91 to 40 actuate mechanism for moving the gears of the reversing mechanism into neutral position, as shown in Fig. 6. After the machine has been thus stopped the filled reel can be removed and replaced by an empty reel.

In order to restart the machine the starting lever 114 is actuated to move the reversing bar an additional distance in the same direction as it is moved by the nut 52 and abutment 88. Such movement causes the cam and the cam plate 103 50 to actuate the starting mechanism and simultaneously to cause the cam of the cam plate 91 to move the reversing gears in a direction which will cause rotation of the screw in the opposite direction to which it has been previously rotated.

By reason of the construction above described an impregnated and coated cord or a fuse, such as a quick match or black match, can be made with great rapidity and of great length and properly reeled to permit a large quantity to be conveniently dried and otherwise prepared for use.

It will be understood that the particular embodiment of the invention shown and described is of an illustrative character and not restrictive 65 and that various changes in form, construction and arrangement of parts, or equivalent mechanism substituted within the meaning and scope of the following claims.

Having thus described the invention, what is 70 claimed as new, and desired to be secured by Letters Patent, is:

1. A machine for making an impregnated twisted cord which comprises a reservoir containing a suitable impregnating material, means 75

- for drawing a plurality of fibrous strands in converging relation through the material in said reservoir to impregnate the several strands and simultaneously twisting said strands within said
5. material to embed said material within the entwined strands, a reel, means for continuously rotating said reel, means for guiding the impregnated cord to said reel, means for moving said guiding means longitudinally of said reel at a
- 10 predetermined rate in non-contacting spirals upon said reel, and automatically operable means for stopping the machine when a predetermined length of cord has been wound upon said reel.
2. A machine for making fuses which comprises
- 15 a conical reservoir containing a combustible match-impregnating composition, a rotatable carrier having mounted thereon a plurality of fibrous-strand carrying cops located above said reservoir, means for continuously drawing said
- 20 strands in converging relation through the lower end of said conical reservoir, means for rotating said carrier to twist said strands within said impregnating composition and to embed said impregnating composition within the entwined
- 25 strands, a positively driven reel for said entwined strands, supplemental coating and guiding means comprising a reservoir containing said impregnating composition located between said reservoir and said reel and having guiding means for di-
- 30 recting said entwined strand through the impregnating composition therein and delivering the same directly to the reel and traversing means for moving said supplemental coating and guiding means longitudinally of said reel at a predeter-
- 35 mined rate thereby to lay said strands on said reel in equally spaced non-contacting spirals.
3. A machine for making fuses which comprises
- 40 a conical reservoir containing a combustible match-impregnating composition, a rotatable car-
- 45 rier having mounted thereon a plurality of fibrous-strand carrying cops located above said reservoir, means for continuously drawing said strands in converging relation through the lower end of said conical reservoir, means for rotating
- 50 said carrier to twist said strands within said impregnating composition and to embed said impregnating composition within the entwined strands, a positively driven reel for said entwined strands, guiding means for directing said entwined
- 55 strands to said reel, traversing means for moving said guiding means longitudinally of said reel at a predetermined rate thereby to lay said strands on said reel in equally spaced non-contacting spirals, and automatically operable means for
- 60 stopping the machine when a predetermined length of fuse is wound upon said reel.
4. A machine for making fuses which comprises
- 65 a conical reservoir containing a combustible match-impregnating composition, a rotatable car-
- 70 rier having mounted thereon a plurality of fibrous-strand carrying cops located above said reservoir, means for continuously drawing said strands in converging relation through the lower end of said conical reservoir, means for rotating
- 75 said carrier to twist said strands within said impregnating composition and to embed said impregnating composition within the entwined strands, a positively driven reel for said entwined strands, guiding means for directing said entwined

of fuse is wound upon said reel, and manually operable means for starting said machine and simultaneously reversing the direction of traverse of said guiding means.

5. A machine for making fuses which comprises

5 a conical reservoir containing a combustible match-impregnating composition, a rotatable carrier having mounted thereon a plurality of fibrous-strand carrying cops located above said reservoir, positively actuated means for continuously drawing said strands in converging relation through the lower end of said conical reservoir, means for rotating said carrier to twist said strands within said impregnating composition and to embed said impregnating composition

10 within the entwined strands, a reel to receive said impregnated entwined strands, means for rotating said reel in properly timed relation to said strand-drawing means, a carriage mounted upon tracks extending longitudinally in parallelism with said reel, guiding means for said entwined strand upon said carriage, a screw engaging a nut on said carriage, reversing gear mechanism for rotating said screw to traverse said carriage in a predetermined direction longitudinally of

15 the reel at a uniform rate to wind said impregnated strand upon said reel in non-contacting spirals, automatically operable means for stopping said machine when a predetermined length of fuse has been wound upon said reel, and means

20 operable to permit the removal of the wound reel.

6. A machine for making fuses which comprises

25 a conical reservoir containing a combustible match-impregnating composition, a rotatable carrier having mounted thereon a plurality of fibrous-strand carrying cops located above said reservoir, positively actuated means for continuously drawing said strands in converging relation through the lower end of said conical reservoir, means for rotating said carrier to twist

30 said strands within said impregnating composition and to embed said impregnating composition within the entwined strands, a reel to receive said impregnated entwined strands, means for rotating said reel in properly timed relation to said strand-drawing means, a carriage mounted upon tracks extending longitudinally in parallelism with said reel, guiding means for said entwined strand upon said carriage, a screw engaging a nut on said carriage, reversing gear mechanism for rotating said screw

35 to traverse said carriage in a predetermined direction longitudinally of the reel at a uniform rate to wind said impregnated strand upon said reel in non-contacting spirals, automatically operable means for stopping said machine when a predetermined length of fuse has been wound upon said reel,

40 and means operable to permit the removal of the wound reel, manually operable means for starting said machine after the substitution of an empty reel, means operable thereby simultaneously to

45 reverse the direction of rotation of said screw, and means for stopping the machine at the end of the return traversing movement.

7. In a machine of the class described having

55 means for drawing a plurality of fibrous strands in converging relation through an impregnating material and for simultaneously twisting the strands within said material to embed said material within the entwined strands, a reel for said inclined strands, and means for guiding said entwined strands from said reservoir to said reel comprising a carriage movable longitudinally of said reel, a nut on said carriage, a screw engaging said nut, and means for rotating said screw in properly timed relation to said drawing means

60

and said reel to wind said strands in non-contacting spirals on said reel, means for arresting the movement of said carriage when a predetermined length of said entwined strands is wound 5 thereupon comprising a bar slidably mounted in parallelism with said screw and having means adapted to be engaged by said nut when the carriage has been moved a predetermined distance, a cam plate connected to said bar having a neutral position and oppositely inclined running positions, a follower for said cam, means actuated by said follower upon longitudinal movement of said cam from an operating to the neutral position to stop said machine, and manually operable 10 means for moving said cam from neutral to operating position.

8. A machine for making fuses which comprises a conical reservoir containing a combustible

match-impregnating composition, a rotatable carrier having mounted thereon a plurality of fibrous-strand carrying cops located above said reservoir, means for continuously drawing said strands in converging relation through the lower 5 end of said conical reservoir, means for rotating said carrier to twist said strands within said impregnating composition and to embed said impregnating composition within the entwined strands, means for supplying the combustible 10 match-impregnating composition to said reservoir comprising a mixing tank, a rotatable mixer therein, and means for rotating the same, and an outlet leading from said tank to said reservoir having a shut-off valve adapted to be opened 15 to replenish the supply of impregnating composition in said reservoir.
